Primary Examiner — Barbara Fox

Assistant Examiner — Dana K Weiland

(74) Attorney, Agent, or Firm — Birch, Stewart, Kolasch
& Birch, LLP(57) **CLAIM**The ornamental design for a portable electronic device, as
shown and described.

DESCRIPTION

FIG. 1 is a front perspective view of a portable electronic
device in accordance with our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines shown in the drawings illustrate portions of
the portable electronic device that form no part of the
claimed design.**1 Claim, 7 Drawing Sheets**(56)
